UNITED STATES PATENT OFFICE.

JOHN R. DE MIER, OF LAS CRUCES, TERRITORY OF NEW MEXICO.

ELECTRICAL FLOAT-SIGNALING APPARATUS.

SPECIFICATION forming part of Letters Patent No. 403,180, dated May 14, 1889.

Application filed August 21, 1888. Serial No. 283,302. (No model.)

To all whom it may concern:

Be it known that I, JOHN R. DE MIER, a citizen of the United States, residing at Las Cruces, in the county of Donna Ana and Territory of New Mexico, have invented certain new and useful Improvements in Electrical Float-Signaling Apparatus; and I do hereby declare the following to be a full, clear, and exact description of the invention, such as will enable others skilled in the art to which it appertains to make and use the same.

My invention consists in the combination of an electrical signaling apparatus, an indicator-float, electrical switch, a battery, and switch-connections with a telegraph-line wire, and to this a thermostat may be added for operating an additional electrical switch by means of the said battery, whereby either high water or fire, or both, may be signaled by a danger-flag at either side of the bridge, and also signaled over the line-wire to the adjacent telegraph-stations.

It also consists in certain other minor combinations, as will be hereinafter described and claimed.

In the accompanying drawings, Figure 1 is a vertical section of the house containing the danger-flag and its operating mechanism, the right side being exposed to view. Fig. 2 is a vertical section of the same, viewed from the left side. Fig. 3 is a vertical section of the same, viewed from the front. Fig. 4 is a vertical section of the upper portion of the same, showing the top open and the "danger-flag" unfurled and thrown out. Fig. 5 is an enlarged view of a clock mechanism used for operating a bell-alarm at the stations and the danger-flag on the roadside. Fig. 6 is a top view of an electrical magnet used for starting the clock mechanism. Fig. 7 is a detail view of its starting rod and lever. Fig. 8 is a top view of said clock mechanism. Fig. 9 is a diagram of the general arrangement of the parts of my invention as applied to a bridge extending over a river. Fig. 10 is an enlarged view of the means for deflecting the line-wire to the clock-work. Fig. 11 is a vertical central section of a float-house containing my float and switch. Fig. 12 is a top view of the thermostat. Fig. 13 is an inverted plan view of the inner mechanism, and Fig.

14 is a vertical central section in the line xx of Fig. 13.

The letter A in the drawings represents a line-wire of a telegraph system; B, a river; C, 55 a bridge; D, a float-house; E, battery; F, flag-house, and G thermostats.

The flag-house F contains a clock signaling mechanism, I, an electric starting mechanism, J, a flag-operating mechanism, K, a switch, L, 60 for the same, a lightning-arrester, M, and a top-lock, N. The signaling mechanism I comprises, principally, an ordinary clock-work, consisting of a main wheel, i^1 , moved by a spring, i^2 , upon the main shaft i^3 , a pinion, i^4 , 65 upon a shaft, i^5 , which latter carries a wheel, i^6 , and signaling-disk i^7 , a pinion, i^8 , upon a shaft, i^9 , carrying an escape, i^{10} , an escape-lever, i^{11} , notched crank-handle i^{12} on the main shaft i^3 , a check and contact-plate, i^{13} , and insulated 70 contact-plates $i^{14} i^{15} i^{16}$, insulating-blocks $i^{17} i^{18}$, as will be further described. The flag-operating mechanism K consists of a flag-staff, k^1 , flag k^2 , furling-rod k^3 , flag-detent k^4 , upright guides k^5 , detent k^6 , chain k^7 , weight k^8 , 75 pulley k^9 , and check-bar k^{10} .

The top f of the flag-house F is hinged at f' to the flag-house, and is at the opposite side locked by the top-lock N to the top portion of the flag-house. This top-lock N consists of a slide-rod, n , properly hung to the flag-house in bearing-supporting brackets n^1 n^2 , an inclined operating end plate, n^3 , and a locking-hook, n^4 , engaging with a pin, f^2 , in the top f , as seen in Figs. 1 and 2. The inclined end plate, n^3 , stands (in its normal position) in the path of the flag-staff k below, so that when the flag-staff rises it strikes the end plate, n^3 , and pushes it and the hook n^4 back, thereby releasing the pin f^2 and the top f .

The electric starting mechanism J consists of an electric magnet, j , armature j' , lever j^2 , check-rod j^3 , with insulated head j^4 , and the usual binding-screws, $j^5 j^6$, as will be further explained.

The clock-work is wound up by the crank-handle i^{11} , and when wound up stands in the position shown in Figs. 1 and 3. A notch, i^{19} , in the said crank-handle stands vertically 100 downward and holds the end portion of the flag-staff detent k^6 , whereby the flag-staff is

held in its lowered position. In this position the crank-handle i^{11} is in contact with the contact-plate i^{14} . This contact-plate is insulated at i^{16} from the contact-frame I', and is, 5 by means of the insulated conducting-wire a , connected with the line-wire of the telegraph, as will be seen. From the frame I' of the clock-work at i^{20} another conducting-wire, a' , serves as connection between the clock-frame 10 and the aforesaid line-wire A.

Between the line-wire and clock-work the wires a a' pass through the lightning-arrester M, which will be described later on. The line-wire A is prevented from conducting its 15 current past the wires a a' by being severed between said two wires and held together by a tubular insulator, A', having an outer annular groove, a^2 , around which the one end portion of the severed line-wire is wrapped 20 and fastened, while the other end portion is passed through the insulation and fastened together outside of it, as is plainly shown in Fig. 10. The currents of the line-wire are thus caused to follow the wires a a' and pass 25 through the clock-work I. The wire a is connected to the contact-plates i^{15} i^{13} i^{14} , and the wire a' at i^{20} to the frame of the clock-work. The contact-plate i^{14} closes the circuit of the line-wire while the clock-work is and remains 30 wound up, the contact-plate i^{18} closes the said circuit when the clock-work has run down, and the contact-plate i^{15} causes the signals received from the revolving signal-wheel i^6 to be transferred to the line-wire.

35 When the contact-plate i^{15} is in operation, the contact-plates i^{13} and i^{14} have no electric connection with the clock-frame I', as will be seen. The contact-plate i^{14} is so constructed that it is in contact with the crank-handle i^{11} 40 when the clock-work is fully wound up, and this connection is broken almost immediately as the clock-work begins to move, thus breaking the circuit of the line-wire. Shortly after this the contact-plate i^{15} , in co-operation with 45 the revolving notched signal-wheel i^6 , transfers the signal to the line-wire, and after said signal is fully made the contact-plate i^{12} of the revolving shaft i^2 and a pin, i^{25} , of the signal-wheel i^6 abut and stop the clock-work. 50 At the same time the contact-plates i^{12} and i^{13} meet in contact, and thus again close the circuit of the line-wire, which is then again ready for general telegraphing.

The wound-up clock-work is prevented from 55 unwinding and signaling by having its escape-lever i^{10} held down by the insulated head j^4 of the sliding-rod j^3 . This rod j^3 is pivoted to the lever j^2 , which is linked to and moved by the armature j' of the starting mechanism J.

60 The battery E, a float, d^4 , and a switch, d , in the float-house D are the means of charging the magnet j at high water, thereby withdrawing the insulated head j^4 from the range of the escape-lever i^{10} , with the above-described result. The float-house D is firmly anchored in the river B, and allows the water to enter through a screen, d^7 , and support a

float, d^4 , therein. This float d^4 is provided with vertical guides d^8 d^5 , which are hung in transverse bridge-pieces d^6 of the float-house, 70 and allow easy vertical movement of the float upon the rising or falling water. Above the guide-rod d^8 the switch d is provided, and it is at such height that said guide-rod comes in contact with it at high water. The switch d 75 consists of two angular switch spring-plates, d^1 d^2 , fastened to the float-house so that their free ends stand apart to prevent closing of the circuit of the battery E, with which they are connected by wires e e' , said closing of the 80 circuit being only effected by the rising of the water and float. From the battery the wire e passes into the flag-house to the binding-screw j^6 , and from the binding-screw j^5 wire e' passes into the flag-house from the 85 float-house, thereby connecting with the switch spring-plate d^2 , while the wire e from the other pole of the battery E connects with the switch spring-plate d^1 of the float-house D, thereby establishing the circuit between 90 the battery E and magnet j . The wires e e' may be extended along a bridge, C, as seen in Fig. 9, and there be connected by branch wires e^2 e^3 with thermostats G, for the purpose of giving a fire-alarm. The thermostats 95 consist of a housing, g , closed by a removable bottom, g' , and containing two switch-plates, g^2 g^3 , of which the plate g^2 is rigid, while g^3 is elastic, having a tension toward the plate g^2 , from which it is held apart by a screw, g^4 . 100 The screw g^4 is provided with a head, g^5 , which rests against the outer surface of the housing g , and is united with the screw-body by means of solder, or an alloy, g^6 , of very low melting-point. This head g^5 is parted from 105 the screw g^4 by the melting of the solder, whereupon the plate g^3 comes in contact with the plate g^2 , thereby closing the circuit between the battery and magnet j , and causing the above-described alarm. The wires a a' 110 and e e' are provided with a lightning-arrester, M, which consists of a flat conducting-plate, m , interposed between each of the said four wires, and a large transverse conducting-plate, m' , fastened at a short distance from 115 the plates m , and a ground-wire, m^2 , so that lightning striking the wires and following them down to the conducting-plates m will be attracted by the large conducting-surface m' and leap over the small intervening space to 120 it, and finally follow the ground-wire m^2 and pass into the earth. In order to break the circuit which operates the magnet j after the clock-work is set in motion, a switch, L, is provided, which is interposed between the 125 wire e . This switch consists of a contact-lever, l , pivoted at l' to a conducting-plate, l^2 , connected with one of the severed ends of the wire e , and a fixed conducting-plate, l^3 , connected with the other severed end of the said 130 wire. The short arm of the lever l is in contact with the plate l^2 when in the position shown in full lines in Fig. 2, and the circuit of the magnet j is then closed. The long arm

of the lever l is in range with the weight k^8 , which latter, when descending, strikes said long arm, moves the lever l into the position shown in dotted lines, whereby the circuit of the magnet j is broken and the magnet and battery are set at rest.

When the clock-work is started, the crank-handle j^{11} revolves, and the notch j^{10} , changing its position toward the flag-staff detent k^6 , loses its hold on the same, and it becomes free. The weight k^8 now descends and by means of the chain k^7 and pulley k^9 pulls up the flag-staff k , which in its ascent strikes the inclined plate n^3 , pushes it back and unlatches the roof f , which is almost immediately thrown back by the flag-staff into the position shown in Fig. 4. After this the flag-staff is pulled by the chain k^7 over the upper end of the inner guide, k^5 , toward the roller k^9 , and gradually moves on a slant outward until the detent k^6 strikes the bar k^{10} and stops the movement of the flag-staff. By cutting a notch, k^{11} , in the flag-staff, which comes in line with the top portion of the flag-house, the flag-staff is caused to assume an almost horizontal position. Into that position the flag-staff is moved very quickly and forcibly, and when the notched portion k^{11} strikes the top of the flag-house the metal furling-rod k^2 of the flag is caused by its weight and momentum to leave its detent k^4 and unfurl the danger-flag k' into view as a warning not to cross the bridge. The parts are all again replaced into their normal position by an attendant, who is protected against electrical shocks when winding up the clock-work by an insulating rubber cover, i^{23} , over the handle of the crank-lever i^{11} .

The alarm-signals sent over the line-wires, as described, will in the telegraph-offices connected thereby either sound such signals on a gong in the ordinary way, or by the signal-key of the telegraph-instrument, and a train passing such station will be stopped by the usual danger-signals displayed at any one of the stations; but if the alarm should be given while the train is between said station and the bridge the danger-flag near the bridge, having been thrown out in the manner described, will be displayed to view and the engineer of the train thereby warned in time to stop the train and avoid disaster.

In case of a fire at the bridge, the signals at the stations and the bridge from the thermostats, through the mechanism in the flag-house, will be the same as that produced by action of high water upon the float.

What I claim is—

1. In an alarm-signal apparatus, the combination of a flag mechanism, K, comprising a flag-staff, chain, pulley, weight, flag-furling rod, flag-detent, and a flag-staff detent, an electric signaling mechanism, I, comprising a main driving-wheel, notched crank-handle,

pinion-wheels, signal-disk i^6 , escape-wheel i^9 , 65 escape-lever i^{10} , check and contact plate i^{12} , insulated contact-plates $i^{13} i^{14} i^{15}$, and insulating-blocks $i^{16} i^{17} i^{18}$, clock-starting mechanism J, comprising electric magnet j , armature j' , lever j^2 , check-rod j^3 , having insulated head j^4 , battery E, float d^4 , electric switch d , and connecting-wires $a a', e e'$, and telegraph-line wire, substantially as and for the purpose described.

2. The combination, with the flag-staff, k 75 and float d^4 , of the clock-work I, having escape-lever i^{10} , and magnet j , having a starting-rod, j^3 , and a battery, E, and a float-switch, d , substantially as and for the purpose set forth.

3. The combination of the clock-work I, 80 having crank-lever i^{11} , with notch i^{19} , and flag-staff k , having detent k^6 , chain k^7 , pulley k^9 , and weight k^8 , substantially as and for the purpose set forth.

4. In the described flag mechanism K, the 85 combination of the chain k^7 , pulley k^9 , weight k^8 , flag-staff k , guides k^5 , cross-bar k^{10} , flag k' , unfurling-rod k^2 , and flag-detent k^4 , substantially as and for the purpose set forth.

5. In the described flag mechanism K, the 90 combination of the flag-staff k , the locking-hook n^4 , sliding rod n , inclined plate n^3 , and swinging top f , having locking-pin f^2 , substantially as and for the purpose described.

6. The combination of the switch L, battery E, magnet j , flag-staff k , detent k^6 , notch-lever i^{11} of clock-work I, chain k^7 , pulley k^9 , and flag-staff-operating weight k^8 , substantially as and for the purpose set forth.

7. The combination of the flag mechanism 100 K, comprising a flag-staff, chain, pulley, weight, flag-furling rod, flag-detent, flag-staff detent, electric signaling apparatus I, comprising main driving-wheel, notched crank-handle, pinion-wheels, signal-disk i^6 , escape-wheel i^9 , 105 escape-lever i^{10} , check and contact plate i^{12} , insulated contact-plates $i^{13} i^{14} i^{15}$ and insulating-blocks $i^{16} i^{17} i^{18}$, clock-starting mechanism J, comprising electric magnet j , armature j' , lever j^2 , check-rod j^3 , having insulated head j^4 , battery E, float d^4 , electrical switch d , thermostat G , telegraph-line wire A, and connecting-wires $a a' e e' e^2 e^3$, substantially as described.

8. The within-described signaling apparatus, comprising float, thermostat, switches thereof, starting mechanism J, battery and circuit-wires thereof, signaling mechanism I, and flag mechanism K, whereby signals at stations and at a bridge can be given both by 120 action of high water and fire, substantially as and for the purpose described.

In testimony whereof I hereunto affix my signature in presence of two witnesses.

JOHN R. DE MIER.
